UNITED STATES PATENT OFFICE

126,575

DESIGN FOR A COMBINED LENS AND HEAD FOR FLASHLIGHTS

Cyril P. Deibel, Lakewood, Ohio

Application October 22, 1940, Serial No. 95,988

Term of patent 7 years

To all whom it may concern:

Be it known that I, Cyril P. Deibel, a citizen of the United States, residing at Lakewood, in the county of Cuyahoga and State of Ohio, have invented a new, original, and ornamental Design for a Combined Lens and Head for Flashlights, of which the following is a specification, reference being had to the accompanying drawing, forming part thereof, wherein Fig. 1 is a top plan view of the combined lens and head for

flashlights, showing my new design; Fig. 2 is a side elevational view of the same; and Fig. 3 is a sectional view on the line 3—3 of Fig. 1 with the head omitted for convenience of illustration.

The dominant features of my design reside in the portions represented in full lines.

I claim:

The ornamental design for a combined lens and head for flashlights, as shown and described.

CYRIL P. DEIBEL.
